UNITED STATES PATENT OFFICE

GEORGE AINSWORTH, OF NEW HYDE PARK, NEW YORK

DESIGN FOR A GLASS BOWL FOR SEMIINDIRECT ILLUMINATION

Application filed February 27, 1932. Serial No. 43,024. Term of patent 7 years.

To all whom it may concern:

Be it known that I, GEORGE AINSWORTH, a citizen of the United States, residing at New Hyde Park, in the county of Nassau and State of New York, have invented a new, original, and ornamental Design for a Glass Bowl for Semi-Indirect Illumination, of which the following is a specification, reference being had to the accompanying drawing, forming part thereof.

The figure is a perspective view of the de-

sign for a bowl which is circular in contour and the opposite side of the bowl has substantially the same appearance as the side illustrated in this figure.

What I claim is:

The ornamental design for a glass bowl for semi-indirect illumination as shown and described.

In testimony thereof, I have signed the foregoing specification.

GEORGE AINSWORTH.
